UNITED STATES PATENT OFFICE.

HERBERT A. TUBBS, OF PORTLAND, MICHIGAN.

STEAM-BOILER.

1,132,985.

Specification of Letters Patent. Patented Mar. 23, 1915.

Application filed September 28, 1912. Serial No. 722,503.

To all whom it may concern:

Be it known that I, HERBERT A. TUBBS, a citizen of the United States, and a resident of Portland, in the county of Ionia and State of Michigan, have invented certain new and useful Improvements in Steam-Boilers, of which the following is a specification, reference being had to the accompanying drawings.

This invention relates to water tube steam boilers and steam boiler furnaces and has as its object to provide a boiler and furnace which will be particularly well adapted for apartment house and dwelling steam heating systems in that steam may be generated thereby with an economical consumption of fuel and without the attention of an experienced engineer.

A further aim of the invention is to provide for a more complete circulation of the water and a more complete utilization of the heat generated from the burning fuel, and this is accomplished by subjecting a certain volume of the water to a high degree of heat and the remainder to a less degree of heat in such manner that the first volume will be rapidly converted into steam and the latter will rapidly take its place.

The invention also aims to provide a boiler and furnace which will be simple in construction and not liable to get out of order and which will require little attention while in use.

With these and other objects in view the present invention consists in the combination and arrangement of parts as will be hereinafter more fully described and finally pointed out in the appended claims it being further understood that changes in the specific structure shown and described may be made within the scope of the claims, without departing from the spirit of the invention.

In the accompanying drawings forming a part of this specification and in which like numerals of reference indicate similar parts in the several views: Figure 1 is a vertical longitudinal sectional view through a boiler and furnace constructed in accordance with the present invention. Fig. 2 is a vertical transverse sectional view on the line 2, 2 of Fig. 1. Fig. 3 is a similar view on the line 3, 3 of Fig. 1.

In the drawings, the numeral 1 indicates the rear wall of the furnace, 2 the side walls

thereof, and 3 the front wall. The top wall or arch is indicated by the numeral 4.

The numeral 5 indicates a flue built at the rear of the furnace and the numeral 6 indicates a bridge wall which is located between the front and rear walls and extends from one side wall to the other, as shown in Fig. 3 of the drawings. The furnace is provided with a cement floor 7 which extends between the bridge wall 6 and the rear wall 1 and between the side walls 2, and supported between the said bridge wall and the front wall 3 is a grate 8. The fire box door of the furnace is indicated by the numeral 9 and is arranged in the front wall 3 above the grate 8, and the ash pit door, indicated by the numeral 10 is located below the grate in the said front wall 3.

The boiler embodying the present invention includes a forward tube 11 and a rear tube sheet 12, and expanded at their ends in these tube sheets are water tubes 13 and steam tubes 14 and 15. The tubes 13 are arranged in staggered relation as shown in Figs. 2 and 3 of the drawings and the tubes 14 and 15 are located above the bank of water tubes, the tube 15 being of greater diameter than the tubes 14 and being located between and above the same. A head 16, of cast or sheet metal and of concavo-convex form, is provided with a peripheral flaring rim 17 and a flange 18 which extends around the margin of the rim 17 and is secured by means of bolts 19 to the forward tube sheet 11 as illustrated in Fig. 1 of the drawings. A similar head 20 is secured to the rear tube sheet 12, and stays 21 are secured at their ends through the said heads 16 and 20 and extend through the water tubes 13 and serve to brace the heads against the pressure within the boiler.

As illustrated in Fig. 1 of the drawings, the boiler proper is arranged within the furnace with its forward head exposed at the front wall of the furnace and its rear head located in advance of the rear wall thereof, at the lower end of the flue 5. The boiler is of course arranged between the upper side of the bridge wall 6 and the arch wall 4, and the said bridge wall is so located as to extend transversely beneath the boiler proper at a point substantially midway between the ends thereof. A baffle plate 22 is supported by the bridge wall 6 and extends thereabove substantially in a vertical plane,

and the water tubes 13 extend through this baffle plate as illustrated in Fig. 1. The upper edge of the baffle plate, however, terminates below the under sides of the steam tubes 14 and 15, and it may be preferable 5 to locate one or more series of the water tubes above the upper edge of the said plate as shown in the drawings, although this is optional. A steam outlet pipe 23 opens 10 through the forward head 16 of the boiler and located upon the said head above this pipe is a pressure gage 24. A water gage 25 is arranged upon the said head 16 below the outlet pipe 23.

15 From the foregoing it will be readily understood that the heat currents from the fuel upon the grate 8 pass upwardly in front of the baffle plate 22 and around the forward portions of the water tubes 13, thereby heating the water in this portion of 20 the tubes to a high degree of temperature. They then pass over the upper edge of the said plate as indicated by the arrows in Fig. 1 of the drawings and around the rear end 25 portions of the tubes, after which they pass up behind the rear head 20 of the boiler and out through the flue 5. It will be observed that the water tubes as well as the steam tubes are inclined downwardly and rearwardly and 30 that the forward or upper ends of the water tubes are subjected to the highest degree of heat, the water in this portion of the water tubes being partially converted into steam before entering the steam tubes 14 and 15 35 which are above the normal water level. In this manner, the water in the forward portions of the water tubes is rapidly converted into steam and the water in the rear portion thereof is heated to such degree as to insure 40 of its quick passage into the forward end portions of the tubes to take the place of

the water which has been subjected to the higher degree of temperature.

Having thus described my said invention, what I claim as new and desire to secure by 45 United States Letters Patent is:

1. In a heating apparatus of the character described, a furnace including a bridge wall, a boiler having oppositely disposed boiler heads comprising an inner substantially flat 50 sheet and an outer curved sheet having at its periphery an offset flange engaging directly the inner flat sheet and detachably connected thereto, said inner sheets having tube openings therein, water tubes having their 55 opposite ends held within said openings, stay bolts passing through said tubes and water heads, and secured to the outer face of the water heads, a relatively large steam tube projecting between the water heads 60 substantially midway of the sides thereof, and a relatively small steam tube at opposite sides of the first mentioned steam tube and connecting with the water heads at its 65 respective ends.

2. A boiler including oppositely disposed water heads, each comprising an outer plate having an outwardly directed securing flange, and an apertured inner plate secured to the flange of the outer plate, said plates located 70 opposite one another, bolts to detachably secure said plates of the heads together, tubes having their ends fitted into said apertures, threaded stay rods extending through said tubes and heads, and nuts to secure said 75 stay rods, as and in the manner set forth.

In testimony whereof I affix my signature, in presence of two witnesses.

HERBERT A. TUBBS.

Witnesses:

F. J. BADGLEY,

FRANK D. LOCKWOOD.
